Thomas J. Christy

UNITED STATES PATENT OFFICE.

THOMAS J. CHRISTY, OF OLNEY, ASSIGNOR TO FRANCIS M. GOODALL, OF MARION, ILLINOIS.

RAILROAD CHAIR AND JOINT.

SPECIFICATION forming part of Letters Patent No. 271,573, dated January 30, 1883.

Application filed September 20, 1882. (No model.)

To all whom it may concern:

Be it known that I, THOMAS J. CHRISTY, a citizen of the United States, and a resident of Olney, in the county of Richland and State of Illinois, have invented a certain new and useful Improvement in Railroad Chairs and Joints; and I do hereby declare that the following is a full, clear, and exact description of the same, reference being had to the accompanying drawings, forming a part of this specification.

My invention relates to certain improvements in that class of railroad chairs and joints in which the base or bottom of the rail or rails rests upon a base-plate, with side plates embracing the web and flanges of the rail, and which are held in place by means of spikes passing down through such side plates, base-plate, and the railroad-tie upon which the parts are supported; and the object of my improvement is to provide a means whereby such side plates or clamps are firmly forced against the sides of the rail, so as to effectually and firmly support the same in proper position, and prevent any movement or play of the parts upon each other. I attain this object by the mechanism illustrated in the accompanying drawings, in which—

Figure 1 is a detail perspective view of the supporting base-plate and side clamping-plates in position to receive the rail. Fig. 2 is a transverse section, illustrating the parts in proper position, with the securing-keys ready to be driven into place. Fig. 3 is a similar view with the said securing-keys driven into place.

Referring to the drawings, A represents the railroad-rail, B the side clamping-plates, D the supporting base-plate, and F the railroad-tie. The clamping-plates B and base-plate D are provided with vertical openings or key-slots C E, through which the headed keys G are driven down into the tie F, to clamp the plate B firmly against the sides of the rail and hold the parts in position on the tie.

The difficulty heretofore met with in this

class of joints and chairs has been that no means were provided whereby the side plates were caused to firmly clamp and hold the rail, and consequently the rail was but poorly held, and the parts allowed to work upon each other and become quickly worn out or broken. To avoid such defective construction is the object of my present improvement, which consists in forming the securing-keys G, with inwardly-tapering sides g, as shown, so that when driven into the tie F the tendency will be to drive outwardly, (as clearly shown in Fig. 3,) thus causing its head to come forcibly against the inner sides, c, of the key-holes C of the clamping-plates B and force the same securely against the rail, the outer sides, e, of the base-plate holes E forming an abutment or fulcrum for the shank of said key in manner clearly indicated in Fig. 3 of the drawings. By this means the parts are firmly clamped and held together, and the objections heretofore existing against this class of joints or chairs are entirely overcome.

In order to prevent "creeping" of the rails in this class of chairs and joints, I nick or cut out a portion of the rail-base and form additional holes through the clamping-plates B and base-plate D, to permit of a spike being driven down through same, and thus prevent any creeping action of the rails taking place.

Having thus fully described my invention, what I claim as new, and desire to secure by Letters Patent, is—

A rail chair or joint consisting of clamping-plates B and base D, provided with key slots or holes C E, in combination with the securing-keys G, having inwardly-tapering sides g, as described, and for the purpose set forth.

In testimony whereof I have hereunto set my hand this 15th day of September, 1882.

THOMAS J. CHRISTY.

In presence of—

ROBERT BURNS,
CHARLES PICKLES.
